UNITED STATES PATENT OFFICE.

SAMUEL JAMES BAWMAN WHITED, OF SHREVEPORT, LOUISIANA.

DUST AND LINT COLLECTING SYSTEM.

1,336,007.

Specification of Letters Patent.

Patented Apr. 6, 1920.

Application filed July 13, 1917. Serial No. 180,335.

To all whom it may concern:

Be it known that I, SAMUEL J. B. WHITED, a citizen of the United States, and a resident of Shreveport, in the parish of Caddo and State of Louisiana, have made certain new and useful Improvements in Dust and Lint Collecting Systems, of which the following is a specification.

My invention relates to improvements in dust and lint collecting systems, and it consists in the combinations, constructions and arrangements herein described and claimed.

An object of my invention is to provide a system for collecting lint which will obviate the necessity of much labor in collecting the same, and which will at the same time render the lint more valuable in that it is collected free from dust and grease.

A further object of my invention is to provide a lint collecting system for use primarily with linter machines in cotton seed oil mills, thus dispensing with the necessity of condensers.

Other objects and advantages will appear in the following specification and the novel features of the invention will be particularly pointed out in the appended claims.

The invention is illustrated in the accompanying drawing forming part of this application, in which:

Figure 1 is a side view of the lint collecting system.

Fig. 2 is a plan view.

Fig. 3 is a perspective view of one of the air regulators, and,

Fig. 4 is a perspective view of the draft regulator.

In carrying out my invention I provide a main suction pipe 1, which is provided with branch pipes 2, leading to hoods 3, which are disposed adjacent to the linters 4, and which are designed to receive the lint from the linters.

In Fig. 2 I have shown two of the linters 45 as being connected with the main pipe 1, but it is obvious that any number might be connected with this pipe without departing from the spirit of the invention.

Each pipe 2 is provided with an air regulator 5, such as that shown in Fig. 3. This consists of a slidable plate arranged to cover or uncover an opening 5^a in the pipe 2. The plate 5 may be moved so as to regulate the size of the opening. The pipes 2 are also provided with draft regulators 6, this being 55 in the form of a damper, having a handle 7

by means of which the draft may be regulated. The pipe 1 communicates with a suction fan 8, of any suitable type, and this suction fan in turn communicates by means of a discharge pipe 9 with a large dust collector 10. The latter consists of a casing having an air tube 10^a extending downwardly from the top, and being provided with an open flared end 10^b. A conical shaped baffle 10^c is carried by a cross member 10^d. The air entering the casing, passes downwardly and thence upwardly through the pipe 10^a, the lint and dust passing downwardly. The air separator communicates by means of a pipe 11 with a small collector 12, having an outlet 13. The small separator is similar in construction to the large separator having a tube 12^a and a baffle 12^b for causing the air to flow upwardly, while the dust and the lint passes downwardly out through the bottom of the collector.

From the foregoing description of the various parts of the device the operation thereof may be readily understood.

The suction or exhaust fan 8 is set in motion, and the lint and dust from the linters is drawn through the branch pipe 2, through main pipe 1 and through the fan 8, and through the discharge pipe 9 into the large dust collector 10, and thence passes by means of pipe 11 into the small collector 12. The air regulating device 5 is for the purpose of regulating the amount of air required for each linter. The idea is to draw up the lint or short fiber by the suction of the fan, without taking up the motes or hulls. The provision of the small collector which receives the lint from the large dust collector eliminates practically all down draft. It also tends to separate the dust from the lint, so that when the lint is delivered through the pipe 13 into any suitable receptacle such as a press or baler it is in a condition which will bring good prices because of the fact that it is clean.

The draft may be regulated by means of the draft regulator 6, so that the proper air current is supplied to each linter. The arrangement besides taking off the short fiber carries off the small flying particles of lint that heretofore have been almost unbearable to workmen and also a loss to the oil mill.

I claim:

1. In a dust and lint collecting system, a plurality of linters, a main suction pipe, an individual branch pipe for each linter, con-

- necting the same with said main suction pipe, a discharge pipe leading from said suction pipe, a dust collector at the end of 15 said discharge pipe, a lint collector communicating with said dust collector and adapted to receive lint from the latter, and means in each of the branch pipes for regulating the amount of air drawn in through said branch pipes.
- 10 2. In a dust and lint collecting system, a plurality of linters, a main suction pipe, an individual branch pipe for each linter con-
- necting the same with said main suction pipe, a discharge pipe leading from said suction pipe, a dust collector at the end of 15 said discharge pipe, a lint collector communicating with said dust collector and adapted to receive lint from the latter, means in each of said branch pipes for admitting air thereto to regulate the amount 20 of air drawn in from the linter, and a damper carried by each of said branch pipes for regulating the draft through the pipes.

SAMUEL JAMES BAWMAN WHITED.
